UNITED STATES PATENT OFFICE.

WILLIAM HENRY ALBEE, OF MARLBORO, MASSACHUSETTS, ASSIGNOR TO KOEHLER MANUFACTURING COMPANY, OF MARLBORO, MASSACHUSETTS, A CORPORATION OF MASSACHUSETTS.

FOOTBALL-CLEAT-APPLYING TOOL.

Application filed October 4, 1922. Serial No. 592,332.

To all whom it may concern:

Be it known that I, WILLIAM HENRY ALBEE, a citizen of the United States, residing at Marlboro, in the county of Middlesex and State of Massachusetts, have invented certain new and useful Improvements in Football-Cleat-Applying Tools, of which the following is a specification.

It has been a common custom heretofore to equip a football shoe with cleats by assembling lifts of leather to form cleat blocks or blanks, nailing the desired number of these blocks on the bottom of a shoe, and then trimming them with a knife or with a chisel to give them the desired shape. This process obviously was expensive in labor, it involved great danger of damaging the shoe, and it produced cleats which were not uniform in shape or appearance.

With a view to overcoming the difficulties experienced in practicing this process, it has been the custom more recently to manufacture the cleats and then to nail the finished cleats on the bottom of a shoe. While this practice is a substantial improvement on the earlier process, it is, nevertheless, open to the objection that the cleats frequently split or crack while the nails are being driven through them, thus necessitating the removal of the defective cleat with the consequent destruction of the cleat, loss of time, and damage to the shoe. A further objection to this practice is that the cleats are often damaged by the nails being driven too far, and while this damage may not be sufficient to necessitate the replacement of the cleat, still it detracts substantially from the appearance of the shoe.

With these considerations in view, the present invention aims to devise a tool for use in affixing football cleats to the bottom of a shoe which will reduce the labor involved, will prevent the splitting or deforming of the cleat, will avoid the bending of the nails which frequently occurs when they are driven in the usual manner, and will leave the cleats presenting a substantially uniform and finished appearance.

The nature of the invention will be readily understood from the following description when read in connection with the accompanying drawings, and the novel features

will be particularly pointed out in the appended claims.

In the drawings, Figure 1 is a vertical cross sectional view of a tool embodying the invention in the form at present preferred, this view also showing the manner in which a cleat is affixed to a shoe;

Fig. 2 is a side elevation of the tool shown in Fig. 1;

Fig. 3 is a bottom view of the tool; and Fig. 4 is a perspective view of the cleat.

Referring first to Fig. 4, a common form of football cleat is illustrated at C, this cleat consisting of several lifts of leather cemented together and having substantially the shape of the frustum of a cone. Before the cleat is attached, holes are punched almost through it, and several nails 4 are driven nearly through the cleat.

In this condition the cleat is placed in the desired position on the bottom of a shoe S, Fig. 1, the shoe at this time being supported on an iron last 6 which is inserted therein.

The attaching tool shown comprises an elongated body 7, preferably of cylindrical form, provided at its lower end with a cavity 8, the walls of which are tapered to fit the lateral faces of the cleat C. Opening into the upper end of the cavity 8 are several nail guiding holes 10 designed to receive the nails 4 which project from the top of the cleat. Each of these holes has a driver 12 slidably mounted therein, and the several drivers are secured in the lower end of a driver bar or plunger 14 which is slidably mounted in the body 7. The upper end of the driver bar carries a head 15 which is adapted to strike the upper end of the body and limit the downward movement of the drivers. The parts are so proportioned that at this time the lower ends of the drivers 12 project very slightly beyond the lower ends of the holes 10. In order to prevent the driver bar 14 from turning in the body 7, the bar is grooved, as shown at 16, and a set screw 17 threaded through the wall of the body has its end located in said groove. This arrangement also limits the upward stroke of the driver bar.

In using the tool the cleat C is placed in the cavity 8 with the nails 4 projecting into

the holes 10, as clearly shown in Fig. 1. The cleat is then moved to the desired position on the shoe while still held in the cavity, and the workman strikes the head of the driver bar 14 with a maul or mallet, thus driving all four nails at once. Obviously the driving of the nails can be done by power if desired. Inasmuch as the cleat fits snugly within the cavity 8, it is effectually prevented from splitting or being otherwise damaged. It is obvious that the nails cannot be bent or driven improperly when this tool is used; and the limiting of the stroke of the driver, as above described, prevents overdriving the nails. The cleats applied with this tool therefore present a neat, finished, and uniform appearance.

It will be understood that if a different form of cleat is to be used, a tool having a cavity to fit it should be provided.

While I have herein shown and described the best embodiment of my invention, of which I am at present aware, it will be appreciated that the invention is not limited to embodiment in the precise form shown.

Having thus described my invention, what I desire to claim as new is:

1. A football cleat attaching tool, comprising an elongated body having a cavity in one end thereof, said cavity having inclined walls to fit snugly against the tapered sides of a football cleat, a series of nail guiding

holes opening into the upper end of said cavity, drivers slidably mounted in said holes, a driver bar slidably mounted in said body and having a head to engage said body at the end of its driving stroke, and means for preventing said driver bar from turning in the body.

2. A football cleat attaching tool, comprising an elongated body having a cavity in one end thereof in which a football cleat will fit snugly, a series of nail guiding holes opening into the end of said cavity, drivers slidably in said holes, a driver bar slidably in said body and having said drivers secured thereto, and means for limiting the driving stroke of said bar so that the ends of the drivers cannot project substantially into the space in said cavity occupied by the cleat.

3. A football cleat attaching tool comprising an elongated body adapted to be held in the hand, said body having a tapered cavity in one end thereof to receive a cleat and confine the lateral faces of the cleat while fastenings are being driven through it, nail guiding holes formed in said body and opening into the end of said cavity, drivers slidably in said holes, and a bar slidably mounted in said body and secured to said drivers, said bar having a head projecting out of the body and adapted to be struck by a mallet.

WILLIAM HENRY ALBEE.
